Atty.

UNITED STATES PATENT OFFICE.

RUSSELL A. FRISBIE, OF MIDDLETON, CONNECTICUT, ASSIGNOR TO THE J. & E. STEVENS COMPANY, OF CROMWELL, CONNECTICUT, A CORPORATION.

TOY TAPE PISTOL.

Application filed March 9, 1927. Serial No. 174,049.

My invention relates to improvements in toy tape pistols of the form that is loaded with paper caps in strip form, arranged in a coil, and fires the caps successively in response to correspondingly repeated operation of the trigger and involving mechanism for feeding the tape to the anvil and hammer; and the object of my improvement is to produce a toy tape pistol involving simplicity and economy in construction and convenience and efficiency in use, and comprising particularly parts that are constructed and arranged to positively deliver strip with the cap to be fired to the space between the anvil and the hammer just before the release of the hammer and involving as a detail feeding the tape through the structure of the hammer member.

In the accompanying drawing:—

20 Figure 1 is a side elevation of my improved toy tape pistol.

Figure 2 is a similar view of part of the same with the cover turned to the open position so as to permit of loading by inserting 25 the tape roll and inserting the free end through the structure of the hammer member and to the space between the anvil and hammer.

Figure 3 is a similar view on an enlarged 30 scale and with the left casing member removed, exposing the interior structure.

Figure 4 is a similar view with the parts in the position immediately before firing.

Figure 5 is a side elevation of the hammer member, with the checking spring in position.

Figure 6 is a rear elevation of the same.

My improved toy tape pistol comprises a casing 10 that comprises as to the exterior 40 the barrel structure 11 and handle 12 arranged after the usual manner and also the guard 13 at the inner lower junction of said barrel structure and handle. Within the space that is enclosed by the guard 13 is 45 the trigger 14. At the top and at the rear of the barrel structure 11 is an opening in which is exposed the upper portion of the hammer 15 which is opposed to the anvil 16.

The casing 10 is made of shell-like castings, comprising the main part 17 which 50 constitutes the right hand side of the wall structure and is adapted to receive and generally operatively support the interior operating mechanism, comprising various moving parts and springs. Cooperating with

said main part 17 is the closure part 18 that serves generally as a closure for the same and constitutes generally the left hand wall structure, except for the opening that is provided for loading. Said opening 19 is 60 provided in the side of the handle 12, on the left side as shown, and exposed a post 20 for receiving the tape coil 21 and also the channel 22 in the hammer member 23 for the tape end portion and admitting to the 65 space 24 between the hammer 15 and the anvil 16.

The opening 19 is closed by a swinging cover 25 that is pivoted on the rivet 26. The casing parts 17 and 18 are rigidly secured 70 together by means of the rivet 27 that is located adjacent the trigger 14.

Pulling the trigger 14 serves to throw the hammer back through the cooperation of the trigger member 28 with the hammer member 23 for an appreciable amount of movement and up to a certain point, when the tripping nose 29 on the trigger member 28 slips by the cooperating nose 30 on the hammer member 23. At this point the hammer member 23 is released and is moved to effect the firing by the hammer spring 31. Upon releasing the hold on the trigger 14 the trigger member 28 is restored to the normal position by the trigger spring 32.

The pivotal support for the trigger member 28 is provided in the form of a knife-edge bearing that is composed of the V-shaped groove 33 on the trigger member 28 and the knife-edge post 34 on the casing.

Said trigger member 28 is in the form of a plate-like structure and comprises adjacent the middle a junction portion 35 at which are merged an upwardly directed horn or arm 36 that supports the V-shaped groove 33; the downwardly directed trigger 14; and the rearwardly directed branch 37 that terminates in the form of the tripping nose 29. Between the horn 36 and the branch 37 is the notch 38 for the spring 32, which extends generally upwardly therefrom and terminates by its upper end in the notch 39 in the casing.

The trigger 14 operates in a slot 40 in the casing.

Normally the cooperating nose 30 is in the path of the tripping nose 29 and is held in such position by the hammer spring 31 and the function of the tripping nose 29 is to tilt the hammer member 23 on its pivot 105 110

41, which movement is continued until the one nose slips past the other. Then the hammer spring 31 restores the hammer member 23 to the normal position. Then follows the release of the trigger 14 and the return of the trigger member 28 to the normal position by the trigger spring 32.

The parts are constructed and arranged so that in such return movement of the trigger member as the noses 29 and 30 coat the trigger member 28 is bodily shifted momentarily to one side to permit the nose 29 to drop below the nose 30. During such shifting the trigger member 28 rides on the pivotal post 34.

The hammer pivot 41 is a knife-edge post supported by the casing and cooperates with a V-shaped groove or recess 42 that is located generally at the lower portion and at the forward side of the hammer member 23, being adjacent the junction of the arm 43 and the wall 44. Said arm 43 is inclined upwardly and forwardly. The wall 44 is the front wall of the channel 22 and the rear face 45 thereof is the way or track along which the free end portion 46 of the cap tape of the coil 19 travels on its way to the hammer and anvil.

At the rear portion of the hammer member 23 is the notch 47 for the upper end of the hammer spring 31. The lower end of said spring 31 is positioned in a notch 48 that is located adjacent the bottom edge of the handle 12.

The notch 47 is at the rear face of a short wall 49 that is separated from the front wall 44 by the channel 22 and is located at the lower entrance portion or mouth of said channel. Said mouth 50 is defined on the front side by an inclined wall face 51 that merges with the face 45 of the wall 44.

The left side of the channel 22 is open to permit of loading and the right side, or bottom, of said channel 22 is provided by part of the web structure 52 that inter-connects the front and rear portions of the hammer member 23.

Located generally in the lower portion of the channel or way 22 and extending upwardly from the mouth 50 is a check spring 53 that operates somewhat after the manner of a pawl to check return movement of the tape end 46 during the feeding and this spring is carried by the hammer member 23.

As shown, said spring 53 has the fixed end 54 in the form of a sleeve that is mounted on a post 55; is upwardly directed from said post 55; abuts against the front face 56 of the short wall 49; and has the free end 57 resiliently opposed to the face 45 of the wall 44. In use, the free end 57 engages with the tape end portion 46 that rides along the face 45.

Spaced upwardly from the short wall 49 is an inclined wall 58 that cooperates with

the opposed wall 44 to define the upper delivery end portion 59 of the channel 22 and that is located immediately below the anvil, 16, and which normally is actually closed by the contacting of the firing face 60 of the hammer 15 with said anvil 16.

The inclined wall 58 and the short wall 49 are virtually parts of the rear wall structure for the channel 22 and which wall structure is interrupted by the opening or separating space 61. Said space 61 is provided for the passage of the feeding pawl 62. Said pawl 62 is inclined upwardly and forwardly from the pivotal post 63 that engages with its lower end and is held seated on said post by the pawl spring 64.

Thus the free end 65 of the pawl 62 is held in resilient engagement with the opposed face 45 of the wall 44 or with the tape end 46 positioned therebetween. The tilting of the hammer member 23 already described is opposed by the pawl 62. As such tilting progresses the pawl end 65 is pushed backwardly and upwardly, carrying with it the tape and thus effecting the feeding thereof to the anvil 16, or to the space 24 between the hammer 15 and the anvil 16.

The length of the tape that is fed for each movement is determined by the extent of the relative movement of the end of the pawl 62 and opposed face 45 of the wall 44. In this detail, I find that a slight though appreciable increase in the length of feed may be obtained by providing a rounded depression 66, as shown, in the face 45 for the opposed free end 65 of the pawl 62.

The feeding is effected as the hammer is swung rearwardly; the portion of the cap tape that is projected into the space 24 is fired by the hammer striking thereon in co-operation with the anvil; the check spring prevents retrograde movement of the tape; and the pawl engages with a part of the tape just above the check spring, ready for again feeding the same.

The hammer member 23 is located just above the tape coil 19 that is housed within the handle 12 and in the feeding the tape is delivered from the coil directly through the structure of the moving hammer member to the anvil.

I claim as my invention:

1. A toy tape pistol comprising a casing having an anvil and a chamber for housing a tape coil of paper caps, mechanism housed within said casing comprising a trigger and means cooperating with said trigger for delivering tape from said coil to said anvil and having a hammer for cooperating with said anvil in firing, said means comprising a pivotally supported hammer member that supports said hammer, said hammer member having a face that serves as a way for the delivery of said tape, a check device for said tape carried by said hammer member, and

a feeding pawl for cooperating with said face supported from said casing.

2. A toy tape pistol as described in claim 1, said face having a depression in registration with said pawl for increasing the relative length of movement of said pawl and face.

3. A toy tape pistol as described in claim 1, a trigger member supporting said trigger, means for operatively supporting said trigger member, and said means comprising a

knife-edge bearing structure and a trigger positioning spring.

4. In a toy tape pistol comprising a casing having an anvil, a hammer member having a hammer, supported for pivotal movement, and having a face for backing a tape end, and means for cooperating with said face comprising a check device supported by said hammer member and a feeding pawl supported from said casing.

RUSSELL A. FRISBIE.
